UNITED STATES PATENT OFFICE

ALEXANDER BURGER, OF NEW YORK, N. Y.

FOLLOWER FOR FILING-CABINET DRAWERS

Application filed March 7, 1929. Serial No. 345,113.

This invention relates to filing cabinet drawers, and has particular reference to an improvement in the adjustable follower which is employed for the purpose of holding the filed articles in a substantially upright position in the drawer.

Primarily, the invention comprehends a filing cabinet drawer equipped with means on the bottom wall affording longitudinally spaced keepers, together with a follower having detent means adapted to engage with said keeper means to lock the follower against movement in one direction while permitting a slightly retarded movement of the follower in the opposite direction.

More specifically, the invention contemplates detent means consisting of an inverted U-shaped member carried and guided by the follower which is formed with beveled extremities at the free lower ends of its legs engageable with the keepers in the manner of a ratchet, together with means engaging the bight portion of said member for urging the same in a direction to engage the beveled terminals with the keepers and for tensioning the same against opposite movement.

Other features of the invention reside in the comparative simplicity of construction and mode of operation of the detent means and the construction of the follower for accommodating the same, the economy with which the same may be produced and the general efficiency derived therefrom.

With the above recited and other objects in view, reference is had to the following description and accompanying drawings, in which there is exhibited one example or embodiment of the invention, while the claims define the actual scope of the same.

40 In the drawings:

Figure 1 is a plan view of a filing cabinet drawer equipped with a follower constructed in accordance with the invention.

Figure 2 is a side view of the drawer with parts broken away and shown in section to disclose the underlying structure.

Figure 3 is a transverse sectional view on an enlarged scale taken approximately on the line indicated at 3—3 in Figure 2.

50 Figure 4 is a fragmentary sectional per-

spective view illustrating the detent engaged with the keeper means.

Referring to the drawings by characters of reference, the drawer, which is preferably of sheet metal construction, includes a bottom wall 5, upstanding marginal side walls 6, a front wall 7 and a rear wall 8. The bottom wall 5 is formed with a plurality of longitudinally spaced keepers 9 on its upper surface, which are preferably defined by a transversely spaced pair of longitudinally disposed strips 10, which strips are provided with the keeper apertures 9. It is, of course, understood that the keepers 9 may be formed in any other equivalent manner. The side walls 6 are provided with longitudinally extending outwardly offset portions 11 adjacent their upper edges defining horizontal shoulders 12 and the offset portions 11 have attached thereto strips 13 formed with inwardly extending flanges 14 and a depending bead 15 at the free edge of said flanges. The strips 13 extend from the front wall 7 rearwardly to a point spaced from the rear wall 8 for a purpose which will hereafter appear.

The follower consists of a plate or sheet of material 16 which approximates the cross sectional area of the drawer and which has secured thereto angle members 17, the right-angularly disposed terminals 18 of which extend beyond the side edges of the follower and are received within the grooves 19 which are defined by the offset portions 11 and the strips 13 so as to guide the follower within the drawer. The spacing of the rear ends of the strips 13 from the rear wall affords the necessary room for inserting the follower in the drawer or removing the same therefrom, thus facilitating the assembly. In order to accommodate the detent means, the upper edge of the follower is bent rearwardly or otherwise formed with a rearwardly extending flange 20 and with a downturned extremity 21 which is disposed in spaced parallel relation to the upper portion of the main area of the follower, the extremity 21 being centrally notched out or cut away as at 22 for a purpose which will be hereafter set forth. The side edges of the follower 16 are rolled inwardly

or otherwise provided with tubular bearings 23 which extend from the lower edge to a point spaced slightly below the lower edge of the extremity 21. The detent means consists of an inverted U-shaped member, preferably in the nature of a rod which presents a pair of parallel legs 24 joined at the upper end by bight 25. The legs 24 are arranged for sliding movement in the tubular bearings 23 while a bowed spring 26 is interposed between the bight 25 and the flange 20 for normally projecting the detent member downwardly and for tensioning the same against upward movement. In order to prevent possible lateral displacement of the spring and at the same time to reinforce the extremity 21 and the flange 20, blocks 27 are arranged between the extremity 21 and the follower plate 16 against the opposite side edges. The lower free ends of the legs 24 are beveled as at 28 to permit the detent means to ratchet over the keepers 9 when the follower is forced forwardly toward the front wall 7 of the drawer. However, the beveled lower ends 28 of the arms 24 function to positively lock and prevent rearward movement of the follower except when the detent member is positively pressed upwardly against the action of the spring 26. This may be accomplished by grasping the top of the follower and exerting an upward pressure with the tips of the fingers, the notched or cut-away portion 22 affording sufficient clearance space therefor.

What is claimed is:

- 35 1. In a filing cabinet drawer, means providing longitudinally spaced keepers and a follower mounted in the drawer for guided movement and having detent means adapted to engage with said keeper means to lock the follower against movement in one direction, said detent means consisting of an inverted U-shaped member carried and guided by the follower and having beveled extremities at the free lower ends of the legs.
- 45 2. In a filing cabinet drawer, means providing longitudinally spaced keepers and a follower mounted in the drawer for guided movement and having detent means adapted to engage with said keeper means to lock the follower against movement in one direction, said detent means consisting of an inverted U-shaped member carried and guided by the follower and having beveled extremities at the free lower ends of the legs and means engaging the bight portion of said member for urging the same in a direction to engage the beveled terminals with the keeper and for tensioning the same against opposite movement.
- 55 3. In a filing cabinet drawer having providing transversely spaced longitudinal rows of keepers on the bottom wall, a follower mounted transversely in the drawer for guided longitudinal movement having vertical tubular bearings adjacent the opposite

side edges and provided with a channel shaped guide at its upper edge, detent means consisting of an inverted U-shaped member including side legs slidable in the guide and a bight portion adjoining the upper ends of the legs slidable in the channel shaped guide and resilient means within the channel shaped guide engageable with said bight for urging the detent means in a direction to normally engage the free ends of the legs with the keepers.

4. In a filing cabinet drawer having means providing transversely spaced longitudinal rows of keepers on the bottom wall, a follower mounted transversely in the drawer for guided longitudinal movement having vertical tubular bearings adjacent the opposite side edges and provided with a channel shaped guide at its upper edge opening downwardly and provided with an upwardly extending medial notch, detent means consisting of an inverted U-shaped member including a bight slidable in the channel shaped guide and depending legs slidable in the tubular bearings and a spring interposed between said bight and the upper closed end of the channel shaped guide for normally projecting the U-shaped member downwardly to engage the free lower ends of the side legs within the keepers.

5. In a filing cabinet drawer having means providing transversely spaced longitudinal rows of keepers on the bottom wall, a follower mounted transversely in the drawer for guided longitudinal movement having vertical tubular bearings adjacent the opposite side edges and provided with a channel-shaped guide at its upper edge opening downwardly and provided with an upwardly extending medial notch, detent means consisting of an inverted U-shaped member including a bight slidable in the channel-shaped guide and depending legs slidable in the tubular bearings and a spring interposed between said bight and the upper closed end of the channel-shaped guide for normally projecting the U-shaped member downwardly to engage the free lower ends of the side legs within the keepers, said free lower ends of the legs being forwardly and upwardly beveled to permit of slightly retarded forward movement of the follower in the drawer and to lock the same against rearward movement in said drawer.

6. In a filing cabinet drawer including bottom, side, front and rear walls, the side walls having longitudinally extending channels formed adjacent the upper edges thereof, and means providing transversely spaced longitudinally extending rows of keepers on the bottom wall; a follower mounted transversely within the drawer for longitudinal movement including laterally projecting guide elements slidable in the channels, tubular bearings adjacent the side edges of the follower, a

rearwardly bent flange at the upper end of the follower having a downwardly bent extremity formed with a medial notch; and detent means consisting of an inverted U-shaped member including side legs slidable in the tubular bearings and a connecting bight at the upper end having guided movement between the flanged extremity and the follower and means disposed between the flange and the bight for urging the U-shaped member downwardly to effect engagement of the free lower ends of the legs with the keepers.

7. In a filing cabinet drawer including bottom, side, front and rear walls, the side walls having longitudinally extending channels formed adjacent the upper edges thereof and means providing transversely spaced longitudinally extending rows of keepers on the bottom wall; a follower mounted transversely within the drawer for longitudinal movement including laterally projecting guide elements slidable in the channels, tubular bearings adjacent the side edges of the follower, a rearwardly bent flange at the upper end of the follower having a downwardly bent extremity formed with a medial notch; and detent means consisting of an inverted U-shaped member including side legs slidable in the tubular bearings and a connecting bight at the upper end having guided movement between the flanged extremity and the follower and means disposed between the flange and the bight for urging the U-shaped member downwardly to effect engagement of the free lower ends of the legs with the keepers, said free lower ends of the legs being upwardly and forwardly beveled to permit of a ratcheting action of the detent means when the follower is moved forwardly in the drawer and serving to positively lock the same against rearward movement.

Signed at New York in the county of New York and State of New York this 5th day of March A. D. 1929.

ALEXANDER BURGER.
